UNITED STATES PATENT OFFICE.

UMBERTO POMILIO, OF TURIN, ITALY.

OXIDATION OF CRESOLS.

1,265,378.

Specification of Letters Patent.

Patented May 7, 1918.

No Drawing.

Application filed August 20, 1917. Serial No. 187,296.

To all whom it may concern:

Be it known that I, UMBERTO POMILIO, technical chemist, a subject of the King of Italy, residing at 20 Via Melezet, Turin, in the Kingdom of Italy, have invented certain new and useful Improvements in or Relating to the Oxidation of Cresols; and I do hereby declare the following to be a full, clear, and exact description of the invention, such as will enable others skilled in the art to which it appertains to make and use the same.

This invention relates to the oxidation of cresols for the purpose of obtaining the corresponding oxyacids or their salts, and more especially for the production of salicylic acid, the chief object of the invention being to utilize an electrolytic method so as to obtain a pure product at a substantial reduction in cost as compared with the chemical methods hitherto employed.

It has been proposed to effect the direct conversion of cresols into the corresponding oxyacids by the fusion of the cresols with caustic alkali and certain metallic oxids at high temperatures, but the reactions are practicable only with a large excess of both the alkali and the metallic oxids. I have found that the metallic oxids and a very large excess of alkali are both unnecessary if an electrolytic method is employed and according to my invention I electrolyze a fused mixture of cresol and caustic alkali so that the oxygen liberated at the anode is absorbed and serves for oxidation of the cresol, while the cathodic hydrogen is set free.

The anodes may be of copper, lead, nickel, iron, steel, nickel steel or other suitable metal, nickel, nickel steel and iron especially being unaffected by the combined action of the current and the alkali. A suitable current density is found to be about 5 to 8 amperes per square decimeter, and the mixture may be heated to a temperature of between 200° and 270° C., the first figure being considerably lower than that necessary for the chemical oxidation referred to.

The following is given as a typical example of a method of carrying out the process as applied to the production of salicylic acid, but the details of the method are sub-

ject to variation and the scale on which the process is worked would determine to some extent the actual steps which are taken:—

Three to five parts by weight of caustic soda with one part of water are mixed in an electrolytic tank or cell and heated to about 110°-120° C. One part of the o-cresol (85 to 95 per cent. o-cresol) is then added in small quantities with constant agitation. A voluminous white mass of sodium cresylate is formed and the temperature is then raised to about 230°-235° C. and the complete fusion of the soda insured. The cresylate partly collects at the top of the fused material as a spongy mass and the amount of material employed should be such that the tank is not more than two thirds filled. The electrodes are then introduced into the tank or cell (which may itself form an electrode), a convenient arrangement being to suspend alternate anodes and cathodes in the form of vertical perforated plates from a cover or support. The current is then passed between the electrodes at a constant anodic current density of about 5 to 8 amperes per square decimeter, while the heating of the cell is so regulated as to keep the temperature during the electrolytic action at about 240° to 250° C. In large scale work external heating may not be necessary but on a smaller scale the temperature may be maintained by external means. It is desirable during the electrolysis to pass some steam through the fused mass by means of iron pipes extending into the cell, in order to prevent packing of the material near the electrodes and to replace the water lost by evaporation and electrolysis.

After about a quarter to a half of the current theoretically required for conversion has passed (about 1.5 ampere hours per gram of cresol is the theoretical quantity necessary) frothing starts and gradually increases in intensity. The material should be stirred to reduce this action, which disappears after about three quarters of the aforesaid theoretical current has passed, the material then becoming more viscous. At this stage the steam supply should be increased and the temperature carefully watched to avoid undue rise. It is found

that the conversion is practically finished when about one-half of the theoretical current has passed.

- The larger proportion of soda mentioned 5 (about 5 parts) is usually preferable and although 3 to 4.50 parts give good yields the electrode voltage is higher during the last stage of electrolysis. Still smaller proportions of the alkali, however can be employed 10 if sufficient provision is made to prevent the packing of the fused mass, for example by mixing some material capable of acting as a flux such as caustic potash with the caustic soda, if the latter is employed, 15 or by the addition of salts (such as borates or acetates) which aid in the fusion of the material. Also, if caustic potash is employed, either wholly or mainly, the proportion necessary may be greatly reduced as 20 compared with the example given for caustic soda; for instance, between one and two parts may be used to one part of cresol. The process is applicable equally to the o-cresol and to impure commercial cresols, which are 25 ortho, meta, and para mixtures the final product resulting in mixed oxybenzoic acid salts that can be more readily separated than the corresponding cresols and are of greater industrial importance.
- 30 The excess alkali can be recovered, for example, by dissolving the product of electrolysis in a small quantity of water and passing carbonic acid gas through the solution to separate the alkali as a carbonate. 35 The salicylic acid can then be precipitated by neutralizing the solution with an inexpensive commercial acid product, such as niter cake, and by completing the precipitation by the addition of sulfuric or hydro- 40 chloric acid. Or the salicylate may be partly

crystallized out by dissolving the product of electrolysis in hot water and allowing the solution to cool.

What I claim is:

1. A process for the oxidation of cresols, 45 in which a fused mixture of cresol and caustic alkali is subjected to electrolysis.

2. A process for the production of salicylic acid or its salts, in which a fused mixture of o-cresol and caustic alkali is sub- 50 jected to electrolysis.

3. An electrolytic process for the oxidation of cresols, in which the cresol is added in small quantities to a fused mass of caustic alkali with a small admixture of water at a 55 temperature of about 110°-120° C. the temperature of the mixture is then raised to about 230°-235° C. and current is passed through the mixture until the oxidation is practically finished.

4. A process for the oxidation of cresols, 60 in which a fused mixture of cresol, caustic alkali, and a flux capable of preventing caking of the product is submitted to electrolysis.

5. A process for the oxidation of cresols, 65 in which a fused mixture of cresol and caustic alkali is subjected to electrolysis, water is added to the resulting product and carbon di-oxid passed therethrough to convert the 70 alkali therein into carbonate, and the oxidized product precipitated by a suitable reagent.

In testimony that I claim the foregoing as my invention, I have signed my name.

UMBERTO POMILIO.
